UNITED STATES PATENT OFFICE

147,998

DESIGN FOR A WASHCLOTH

Frank Vaiana, Alhambra, Calif.

Application February 3, 1947, Serial No. 136,640

Term of patent 14 years

(Cl. D92—26)

To all whom it may concern:

Be it known that I, Frank Vaiana, a citizen of the United States of America and a resident of the city of Alhambra, in the county of Los Angeles, and State of California, have invented a new, original, and ornamental Design for Wash Cloth, of which the following is a specification, reference being had to the accompanying drawings, forming part thereof.

In the drawings:

I claim:

The ornamental design for a wash cloth, substantially as shown.

FRANK VAIANA.
